(57) **CLAIM**

The ornamental design for “windshield mount,” as shown.

DESCRIPTION

FIG. 1 is a perspective view of a “windshield mount” showing my new design;

FIG. 2 is a front view thereof;

FIG. 3 is a rear view thereof, the broken lines being shown to disclaim this portion of the claimed design;

FIG. 4 is a right side view thereof;

FIG. 5 is a top plan view thereof; and,

FIG. 6 is a bottom plan thereof.
